UNITED STATES PATENT OFFICE.

NAJAH CARRINGTON TAYLOR, OF STAUNTON, VIRGINIA.

METALLIC HEAD FOR BARRELS.

Application filed March 1, 1927. Serial No. 171,810.

The present invention is directed to improvements in metallic heads for barrels, kegs, or the like.

The primary object of the invention is to provide a barrel head so constructed that it can be easily and quickly applied to the barrel and firmly maintained in place thereon in a simple and practical manner.

Another object of the invention is to provide a barrel head so constructed that should the upper ends of the staves be out of alignment they will be brought into alignment as the head is applied to the barrel.

Another object of the invention is to provide a barrel head which is practically indestructible under normal conditions and will last indefinitely.

Another object of the invention is to provide a device of this kind so constructed that the upper ends of the staves need not be beveled or otherwise machined to assure proper fit, thereby materially reducing the cost of the barrel.

In the accompanying drawing:

Figure 1 is a fragmentary side elevation of a barrel showing the head in place thereon.

Figure 2 is a top plan view.

Figure 3 is a vertical sectional view through the head, showing it in place upon the upper end of a barrel.

Referring to the drawing, 1 designates a barrel, in this instance formed from a plurality of staves 2 which are of the usual construction with the exception that the upper ends thereof are not beveled, as is customary. These staves are maintained in clamped relationship by the usual hoop 3.

The head 4 is formed from a blank of suitable gage metal and is so formed as to provide a central plate 5 having its periphery terminating in a beveled wall or shoulder 6, which in turn, terminates in a channel member 7, the outer wall of which terminates in a depending side flange 8. It will be observed that the upper plane of the channel member 7 is above the plane of the plate 5 in order that when the head is in place upon the barrel the plate will enter the upper end thereof for a short distance.

The side flange 8 is cut to provide a plurality of substantially V-shaped ears 9, and resultant spaces 10, the lower ends of the ears being turned up to provide seats 11, the purpose of which will later appear.

The head is placed upon the upper end of the barrel and forced downwardly by a block

of suitable formation, and should the upper ends of the staves be cut out of alignment the wall or shoulder 6 will guide said ends to alignment as they enter the channel of the member 7. After the head has been firmly set a wire hoop 12 is placed therearound and forced downwardly until it occupies the seats 11, after which staples 13, or other suitable securing devices are engaged with the hoop at points in the spaces between the ears 9, thereby firmly securing the hoops in place. The plates 5 may be strengthened by providing corrugations 14 which may be of any desired form.

While I have illustrated the head used in connection with a barrel formed from staves, it will be of course understood that it can be used successfully in connection with barrels or kegs formed from fiber.

Having thus described the invention, I claim:

1. A barrel head comprising a metal plate bent in spaced relation to its periphery to form an annular shoulder flat throughout its circumference and extending upwardly at an outward incline and leading to an upstanding circumferentially extending barrel engaging portion of an inverted U-shape in cross section and having inner and outer walls, the outer wall being of greater depth than the inner wall and having slits leading from its lower edge to provide spaced tongues, the free lower ends of the tongues being bent outwardly and upwardly to provide hooked ends, and a securing ring for said head encircling the same about the tongues and engaged by the hooked ends of the tongues when in place.

2. In combination with a container having a frusto-conical end portion, of a cover having a depending inclined annular portion adapted to be forced over the frusto-conical end of said container to close the same, said annular inclined portion having a plurality of openings and being provided with an abutment, a ring adapted to be wedged over the inclined annular portion of said cover until it engages said abutment to hold said cover in place upon the container, and means extending through the openings in the annular inclined portion of the cover for securing said ring to said container.

3. In combination with a container, of a head comprising a plate having a channeled marginal portion inverted U-shape in cross section providing spaced inner and outer up-

standing walls inclined relatively to each other, said outer wall having a plurality of openings and being provided with an abutment, said head adapted to be pressed over the end of said container with the ends of the walls of the container clamped in the channeled marginal portion of said head, a ring adapted to be pressed over the outer

wall of the head into engagement with said abutment for holding the cover in place upon the container, and means extending through the openings in the outer upstanding wall of said head for securing said ring to the container.

In testimony whereof I affix my signature.
NAJAH C. TAYLOR. [L. s.]
